Primary Examiner — Antoine D Davis(74) *Attorney, Agent, or Firm* — Stetina Brunda Garred & Brucker(57) **CLAIM**

The ornamental design for a scan tool, as shown and described.

DESCRIPTION

FIG. 1 is a front perspective view of invention;

FIG. 2 is a bottom view of the invention;

FIG. 3 is a front view of the invention;

FIG. 4 is a left side perspective view of the invention;

FIG. 5 is a top view of the invention;

FIG. 6 is a back view of the invention; and,

FIG. 7 is a right side perspective view of the invention.

The broken line showing of structural feature is included for the purpose of illustrating non-claimed subject matter and forms no part of the claimed design.

1 Claim, 3 Drawing Sheets---
